CRISPER

Cyril J. Yates, Henderson, Ky., assignor to Tri-State Plastic Molding Co., Henderson, Ky., a limited partnership

Application June 2, 1949, Serial No. 2,997

Term of patent 14 years

(Cl. D44—1)

To all whom it may concern:

Be it known that I, Cyril J. Yates, a citizen of the United States and a resident of Henderson, Kentucky, have invented a new, original, and ornamental Design for a Crisper, of which the following is a specification, reference being had to the accompanying drawing, forming part hereof, in which:

Fig. 1 is an exploded perspective view of a crisper, embodying my new design; and

Fig. 2 is a side elevation in section taken along the lines 2—2 of Fig. 1, when the crisper of such Fig. 1 is closed.

I claim:

The ornamental design for a crisper, as shown and described.

CYRIL J. YATES.
